COMBINATION TOOL HOLDER.

Application filed April 21, 1926. Serial No. 103,633.

This invention relates to cutters and holders as used in connection with machine tools in which work parts are caused to rotate as in lathes or reciprocate as in machines of the 5 planer type.

Such cutting tools, forged from tool steel bars, are well known to be so wasteful in construction, tedious to grind and maintain in proper shape, fail in temper or suitable degree of hardness and have so many other causes for dissatisfaction that their use is 10 becoming superseded by tools of more modern character.

The provision of such improved tool holder is therefore the principal object of the present invention.

A further feature is to provide a holder in which may be engaged any of a plurality of reversible "bits" or cutters, diverse in shape 20 to appropriately suit the work to be done and selectively secured in a firm and rigid manner.

Another aim is to produce a novel and efficient fastening means by which the cutters 25 are held substantially as rigid as if they were a unitary part of the holder, enabling their use wherever a solid tool could be employed.

These and analogous features are accomplished by the novel and practical design, 30 construction and combination of parts hereinafter described and shown in the accompanying drawings, forming a material part of this disclosure, and in which:—

Figure 1 is a side elevational view of one 35 type of an improved tool holder, the shank being partially omitted and a cutter shown in operative relation.

Figure 2 is a top plan view of the same, 40 an offset shank being indicated in broken lines.

Figure 3 is a similar side view of the same, broken away to show the construction.

Figure 4 is a view like Figure 3 but showing a modified form of cutter locking device.

Figure 5 is an end view of a cutter, reversible to operate either right or left handed.

Figure 6 is a front elevational view of the same.

Figure 7 is a rear elevational view thereof.

Figure 8 is an end view of a cutter presenting a straight cutting edge at one side and a curved cutting edge at the other, re-

versible at will, a front elevational view being shown therebelow.

Figure 9 is an end view of a finishing 55 cutter, the view below showing gradually converging sides to provide clearance.

Figure 10 is a similar view of a parting cutter with front view underneath, showing its reduced thickness at the back and bottom. 60

Figures 11 to 14 inclusive show profile or outline views respectively or reversible finishing, 70° diamond point, right and left roughing and narrow roughing and 60° angle threading cutters. 65

Figure 15 is a plan view of a boring bar holder interchangeable with the cutters in the holder.

Figure 16 is a similar view of a 60° angle 70 threading cutter.

In common with forged tools and other tool holders the shank 20 of the present holder is an oblong rectangle in cross section, the larger dimension being disposed in position to receive the strain of the cutting 75 action within a tool block of ordinary character.

The shank is integral with a head 21 expanded substantially equal at each side and extended downwardly at its front portion 80 as indicated; the head being straight or at an angle with the shank as preferred.

A recess 22 is formed centrally in the head, open at the front and extending rearwardly to about the junction with the shank, and a narrow slot 23 reaches into the shank a short 85 distance.

The front of the head is cut transversely across the top as at 24 and inclined at an angle rearwardly its full height as at 25, the 90 corners being bevelled as shown.

Adjacent and parallel with the front surface of the head is the recess 22, which is of considerable width with straight parallel walls; the recess is enlarged to present equal, 95 opposed ninety degree openings 26 extending from top to bottom of the holder head.

A pair of clamp bolts 27 and 28 respectively upper and lower, pass squarely through the head, the latter bolt being disposed in the bottom projection of the holder. 100

In the form shown in Figures 1, 2 and 3 a flat lever 29 is shown pivoted on the lower bolt 28, this lever being freely movable in

the recess 22 by pressure applied to its upwardly extending handle portion 30; the main portion fitting the recess snugly to be clamped rigid between its walls when the bolts are tightened.

The front edge of the lever is designed to extend between the bolts and is provided with serrations 32, preferably of 60 degree angle formation.

10 The holder shown in Figure 4 is of like construction but in place of a pivoted cutter grip, has a slide block 35 its lower edge riding on the lower bolt 28 as it moves in the recess 22.

15 The rear portion 36 of the block is slightly thicker, the sides being very slightly tapered towards the front to permit the teeth to engage with the teeth 47 of the cutting tool, even if the clamp jaws 21 and 24 were

20 closed somewhat out of parallelism and extending to the rear edge of the block is a lug 37 engaged in a drilled opening 38 passing through the slot 23 and slightly into the shank. A coiled compression spring 39 is contained in the opening to press the block normally towards the front.

A lever 40 is fulcrumed on the upper bolt 27 to extend into a position conveniently reached in operation and on the lever is an 30 angular tooth 41 engaging in a corresponding notch in the upper edge of the block whereby it may be moved within the recess when the bolts are slackened, thus permitting advance or retraction of the teeth 42 in its forward edge.

Figures 5 and 10 to 13 show some of the more common cross sectional views of metal cutters, in all of which an integral straight rectangular bar 45 forms the rear portion.

40 The opposed angular lateral edges 46 are adapted to closely fit within the tool holder head opening 26 so as to be gripped thereby when the clamp bolts are tightened.

The rear edge of the bar is flattened and 45 has formed throughout its entire length a plurality of transverse serrations 47 conforming and complementary to the teeth 32 or 42.

To release a cutter from the holder indicated in Figures 1 to 3, the bolts are slackened and the lever 30 moved rearwardly to cause disengagement of the teeth, whereupon the cutter may be raised, lowered or removed at will; similarly in the device illustrated in Figure 4, the lever 40 is moved towards the front, causing the block to slide rearwardly to release the teeth.

It is to be noted that the thrust of the cutters is taken mainly by the teeth and 60 not dependent on the clamping effect of the bolts, which serve to lock the levers and block in adjustment, thus allowing the cutters to be easily adjusted.

Cutters may be used of any length compatible with the tool support of the machine

and may be economically produced by rolling into bar form, or by drop forging; those requiring a finished surface or for making a definite formed cut being milled lengthwise to shape.

It is to be seen that the height of the cutters is easily and quickly adjustable, relative to the holder, to bring the point or shearing edge to the axial plane of work-part rotation; it will also be apparent that 75 the tool holder permits being supported close to its front end, due to its shape, preventing any material overhang and providing an adequate support for the cutter.

Certain of the cutters, as shown in Figures 5 to 8, are formed with a rake, that is to say the cutting portions 48 are disposed at an inclination to the square bar portions 45, to provide clearance in operation, and others as in Figures 9 and 10 have their cutting 85 portions 49 slightly reduced in width towards their lower ends, which of course prevents using the same in a reversed position, possible to be done with most of the other cutters.

In order to complete the cutter holder possibilities of the implement, the device shown in Figure 15 may be utilized, the same consisting of a body 48 bored transversely at its upper end to receive a boring bar 49 secured in any preferred manner, as by the screws 50 shown, and in order to secure exceptional rigidity an arm 51 may extend integrally rearward, the same clearing the holder head side 21, against which may impinge the point 100 of a screw 52, acting to transmit a portion of the strain received by the cutter carrying boring bar 49 directly to the tool holder.

It will be understood that other expedients and variations may be resorted to for although we have described our improvements with considerable detail and with respect to certain particular forms of our invention, it is not desired to be limited to such details since many changes and modifications may 110 well be made without departing from the spirit and scope of our invention in its broadest aspect.

Having thus described our invention, what we claim as new and desire to secure by Letters Patent, is:—

1. A tool holder comprising a shank having a widened head notched at its forward corner and having a part extending below the plane of the shank, said head containing an inclined socket of opposed angular formation open at the front and recessed at the rear, a cutter having a part slidable in said socket, teeth on the rear edge as said cutter, a toothed element movable in the recess at 120 the rear of said socket to engage and disengage the cutter teeth, said element having a part extending upwardly through the recess for manual operation, means for supporting said element, and means combined with the 125

supporting means for clamping the element in adjusted position.

2. A tool holder comprising a shank having an enlarged head containing a socket at the front and a parallel walled recess extending centrally therethrough, a cutter engageable in said socket, said cutter being serrated on its rear edge, upper and lower bolts passing transversely through said head and recess, a lever pivoted on the lower bolt to operate between the walls of the recess, a part of said lever extending upwards through the recess facilitating operation, and serrations on the front of said lever engageable with the serrations on said cutter, said bolts when tightened clamping said lever in the recess and said cutter in the socket simultaneously.

3. A tool holder comprising a shank having an enlarged head containing an open angular socket adjacent the front and an open recess at the rear, a cutter having a part engageable in the socket, transverse serrations on the innermost edge of said cutter, a pair of clamp bolts passing through said head, a lever pivoted in the recess on one of said bolts, said lever being reduced in thickness from rear to front and having a handle extending above the plane of said

shank, teeth on the forward edge of said lever engageable with the serrations of said cutter, and means for clamping said lever and cutter simultaneously. 30

4. A tool holder comprising a shank having an enlarged head inclined rearwardly at the front and containing a central slot open at the top, bottom and front, opposed V-shaped angular recesses in the opposite walls of the slot near the front of said head constituting a socket, a cutter having a part 35
slidable in the socket, equilateral teeth disposed transversely across the rear edge of said cutter over the full length thereof, manually operable lever actuated means in the slot movable towards and from the socket, said means nearly filling the slot to act as a spacer, teeth on said means complementary to the teeth on said cutter to engage therewith, and a pair of bolts respectively upper and lower to control the slot and clamp the cutter therein, one of said bolts acting as a pivotal support for said lever means 40
45
50

In testimony whereof we have affixed our signatures.
